US00D951530S

(12) **United States Design Patent** (10) Patent No.: **US D951,530 S**
Klus (45) Date of Patent: **** May 10, 2022**

(54) **EXTRUSION FOR LED BASED LIGHTING APPARATUS**

(71) Applicant: **KLUS, LLC**, Vero Beach, FL (US)

(72) Inventor: **Sylwester Klus**, Kamionka (PL)

(73) Assignee: **KLUS, LLC**, Vero Beach, FL (US)

(**) Term: **15 Years**

(21) Appl. No.: **29/760,847**

(22) Filed: **Dec. 4, 2020**

(30) **Foreign Application Priority Data**

Aug. 17, 2020 (EM) 008123244-0004

(57) **CLAIM**

The ornamental design for an extrusion for LED based lighting apparatus, as shown and described.

DESCRIPTION

FIG. 1 is a bottom perspective view of the extrusion for LED based lighting apparatus, showing the new design;

FIG. 2 is a top perspective view thereof;

FIG. 3 is a front view thereof;

FIG. 4 is a top view thereof;

FIG. 5 is rear view thereof; and,

FIG. 6 is a side view thereof.

The uniformly dashed lines shown in the drawings illustrate portions of the extrusion for LED based lighting apparatus which form no part of the claimed design.

1 Claim, 3 Drawing Sheets
